(57) **CLAIM**

The ornamental design for an autonomous vehicle storage bin/tray, as shown and described.

DESCRIPTION

The present application is related to application Ser. No. 29/491,937, entitled Autonomous Vehicle Overall Interior, to application Ser. No. 29/491,867, entitled Autonomous Vehicle Console, to application Ser. No. 29/491,868, entitled Autonomous Vehicle Seat, to application Ser. No. 29/491,885, entitled Autonomous Vehicle Control Buttons, and to application Ser. No. 29/491,889, entitled Autonomous Vehicle Go/Pull Over Button, each of which is filed concurrently herewith, the entire disclosures of which are incorporated by reference herein.

FIG. 1 is a front perspective view of an autonomous vehicle storage bin/tray according to a first embodiment of our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an autonomous vehicle storage bin/tray according to a second embodiment of our design;

FIG. 9 is a front elevation view thereof;

FIG. 10 is a top elevation view thereof;

FIG. 11 is a front perspective view of an autonomous vehicle storage bin/tray according to a third embodiment of our design;

FIG. 12 is a front elevation view thereof; and,

FIG. 13 is a top elevation view thereof.

Broken lines are environmental only and form no part of the claimed design.
